UNITED STATES PATENT OFFICE.

WYATT C. STAER, OF LAKE WALES, FLORIDA.

LOG UNLOADER.

Application filed August 22, 1925. Serial No. 51,781.

To all whom it may concern:

Be it known that I, WYATT C. STAER, a citizen of the United States, residing at Lake Wales, in the county of Polk and State 5 of Florida, have invented a new and useful Log Unloader, of which the following is a specification.

This invention relates to an unloading device especially designed for unloading logs 10 from cars which carry the logs from the lumber camps to the usual log slip.

An important object of the invention is the provision of a log skid including pivotally supported arms adapted to automatically swing downwardly when they are being passed under logs supported on a car, the arms being supported in such a way that they will automatically move to their active 15 positions, behind the logs to move the logs 20 onto the skid rail.

Another object of the invention is to provide rigid links pivotally supported and connected with the log engaging arms in such a way that the links will fold down out of 25 the way of the arms when the arms are moved to their inactive positions.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed, without departing from the spirit of the invention.

Referring to the drawings:

Figure 1 is an elevational view disclosing a logging skid or log unloader constructed 40 in accordance with the invention.

Figure 2 is a transverse sectional view through the skid.

Figure 3 is a plan view thereof.

Figure 4 is a plan view of one of the log 45 engaging arm carriages.

Figure 5 is a side elevational view thereof.

Figure 6 is a sectional view taken on line 6—6 of Figure 4.

Referring to the drawings in detail, the 50 device includes a skid supporting frame indicated generally by the reference character 5 which supports the skid rails 6 over which the logs are moved on their passage to the log slip indicated at 7, and which is positioned at one end of the frame 5, the log 55

slip being of the usual and well known construction.

Positioned between the rails 6 of the skidway are guideways 7 in which the skidding members 8 move, the skidding member 8 including spaced bars 9 arranged at their ends, between which the log engaging arms 10 are pivotally supported. Shafts 11 connect the arms 9 at the respective ends of the skidding member and act as supports for 60 the arms 10 as clearly shown by Figures 4 and 5 of the drawings, there being provided coiled springs 12 coiled around the shafts 11 and having their intermediate portions bearing against the arms 10 to normally urge 65 the arms to the limit of their upward movements.

Associated with each shaft 11 is a shaft 13 that provides a support for the link 14 at one end of the skidding member, the links 70 14 being supplied with elongated openings 15 that receive the pins 16 that extend laterally from the arms 10, the construction being such that when the arms 10 are moved downwardly to their inactive positions, the 75 links 15 will fall to positions below the upper edges of the arms 9 so that they will not obstruct the movement of the skidding members.

Positioned at the ends of the skidding 80 members and supported between the arms 9 are rollers 17 that support the weight of the skidding members and reduce friction between the skidding members and the guideways in which they move to the minimum. 90

The skidding members 8 are relatively long and as illustrated by Figure 1 of the drawings, are of lengths so that when a skidding member has been moved so that 95 the log engaging arm of one end thereof contacts with logs arranged on a car which has been moved to one end of the frame 5, the log engaging arm at the opposite end of the skidding member will engage the 100 logs which have been moved to a position on the skidways by a previous movement of the skidding member to cause the logs to be moved to the discharge end of the skidway, or to a position adjacent to the log slip 105 where they may be readily moved onto the log slip.

The car which carries the logs from the lumber camp is of the usual construction and includes car bunks 18 between which 110

the skidding members move, the car bunks acting to support the logs in spaced relation with the upper surface of the car so that the skidding members may be readily moved 5 thereunder.

Under each skidding member are spaced flanges 19 between which the pulleys 20 and 21 are mounted, the pulley 20 acting as a means whereby the flexible member 22 10 may be connected to the skidding member, while the pulley 21 acts as a means whereby the opposite end of the flexible member may be connected to the skidding member, the flexible members being wound on the drums 15 23 supported on the shaft 24 which is rotated by means of the gear 25 meshing with the pinion 26 that in turn is mounted on shaft 27 and rotated by gears 28 and 29 of the power device. Thus it will be seen 20 that when the flexible members are wound on the drums 23 in one direction, the skidding members will be moved outwardly or to positions as illustrated by Figure 1 of the drawings, but when the flexible members 22 25 are wound in the opposite directions the skidding members are moved in the reverse direction forcing the logs over the skidway.

The flexible members 22 operate over pulleys 30 and 31 to reduce friction and permit 30 the skidding members to be moved with the minimum amount of power.

In the use of the device, a car such as indicated by the drawings and which has been loaded, is moved to a position adjacent 35 to one end of the skidway supporting frame. The skidding members are now moved to the limits of their outward movements, whereby the log engaging arms 10 automatically move to their active positions or to 40 positions to engage the logs piled on the car. The drums are now reversed and the skid members are moved in the reverse direction, with the result that the arms force the logs over the skidways leaving a pile of

logs at a point substantially intermediate 45 the skidways.

When the skidding members are moved again to a position to engage the logs on a car which has been moved to a position adjacent to the skidway frame 5, it will be 50 obvious that the engaging arms at the forward ends of the skidding members will engage the logs which have been deposited intermediate the ends of the skidways by the first movement of the skidding members 55 to the end that when the skidding members are moved to remove logs from the car, the arms at the forward ends of the skidding members will move the logs engaged thereby to a position adjacent to the log slip 60 where they may be readily slid onto the log slip and carried to the mill.

I claim: —

1. In a log unloading device, a skidway, 65 skidding members movable longitudinally of the skidway, said skidding members including spaced arms arranged at the ends thereof, rollers mounted between the arms, pivoted log engaging members carried by the spaced arms, and means for moving the 70 skidding members.

2. In a log unloading device, a skidway, guideways mounted on the skidway, skidding members movable longitudinally of the skidway and operating within the 75 guideways, each skidding member including spaced arms shafts mounted between the arms, log engaging bars mounted on the shaft, spring members adapted to engage the bars to move the bars to their active 80 positions, pivoted link members engaging the bars and adapted to restrict movement of the bars, and means for moving the skidding members over the skidway.

In testimony that I claim the foregoing 85 as my own, I have hereto affixed my signature.

W. C. STARR.
